PRESERVING RECEPTACLE

Filed Jan. 20, 1922

FIG. 2.

FIG. 1.

INVENTOR

Martin Saloun
BY
Frank J. Schaefer, Jr.
Attorney

UNITED STATES PATENT OFFICE.

MARTIN SALOUN, OF MILWAUKEE, WISCONSIN.

PRESERVING RECEPTACLE.

Original application filed February 12, 1921, Serial No. 444,363. Divided and this application filed January 20, 1922. Serial No. 530,543.

This is a divisional application, being a part of my original application filed February 12, 1921, Serial No. 444,363.

The invention relates to bottles and means for applying thereto or removing therefrom a cap.

It is an object of the invention to provide a bottle which is formed with a depression or seat exteriorly of its neck for the reception of a gasket with which the cap when in closing position enters into engagement.

It is also an object of the invention to provide a cap with a central depression portion capable of receiving a member whereby the cap may be conveniently placed on the bottle neck or removed therefrom.

With these and other objects in view, which will appear as the description of the invention proceeds, the latter comprises the means set forth in the following specification, particularly pointed out in the claim forming a part thereof, and illustrated in the accompanying drawings, in which:

Figure 1 is a sectional elevation of a bottle constructed in accordance with my invention.

Figure 2 is a top plan view of the bottle.

Referring to Figures 1 and 2 of the drawing, 1 generally denotes a bottle which has the form of a so-called Mason jar, but which of course may have any other preferred form or shape to meet special requirements. The bottle 1 is provided with a bottom 2 and with a side wall 3 which maintains uniform cross-section throughout the major portion of its height. At the upper end of the side wall 3 the same is formed with a circumferential bead 4 and thence passes into a horizontal portion 5 of less thickness than the bead 4, so that a circular groove or depression 6 is formed for a purpose hereinafter further referred to. The horizontal portion 5 passes into a vertical portion 7, constituting the neck of the bottle and is provided with corrugations 8 constituting a continuous thread for engagement with a cap, generally indicated by 9. The cap 9 is formed with corrugations 10,

similar to the corrugations 8, so that the cap may be screwed onto the neck or unscrewed therefrom.

As shown in Figure 2, a gasket 11 is arranged in the seat 6 and is adapted to be engaged by the lower edge of the cap which is slightly flared outwardly. It follows therefrom that when the cap 9 is in closing position on the neck, a hermetical seal is formed by virtue of the engagement between the gasket and the cap. The latter is formed at the top with a central diametrically extending groove 12 of rectangular cross-section and interposed between the top of the cap 9 and the upper edge of the bottle neck is a disc 13 which is pressed into contact with the edge of the bottle neck by the cap.

From the foregoing it follows that the bottle is hermetically sealed at the top by virtue of the provision of the gasket and the disc 13 so that air or vapors cannot enter into the bottle nor escape therefrom, which is highly desirable for the proper conservation or storing of the contents intended to be placed into the bottle.

I claim:

A bottle, comprising a body portion having an elongated neck of reduced diameter exteriorly threaded, the upper part of the body extending upwardly to form an annular flange concentric with the neck portion to provide an annular recess in the upper part of the body portion, a gasket positioned in the recess and resting on the upper part of the body, a cup shaped cap threaded on said neck and engaging said gasket, the upper portion of said cap extending upwardly inwardly to form a transverse tool receiving slot of less length than the diameter of the cap, the annular recess being of sufficient depth to accommodate the gasket and a sealing compound placed therein, and a disk interposed between and engaged by the upper edge of the neck and the cap.

In witness whereof, I have hereunto subscribed my name this 14th day of January, 1922.

MARTIN SALOUN.
